UNITED STATES PATENT OFFICE.

BENJAMIN BRODIO, OF NEW YORK, N. Y., ASSIGNOR TO THE SUPERHEATER COMPANY, OF NEW YORK, N. Y., A CORPORATION OF DELAWARE.

SUPERHEAT-REGULATOR.

1,387,463.

Specification of Letters Patent. Patented Aug. 16, 1921.

Application filed May 2, 1918. Serial No. 232,149.

To all whom it may concern:

Be it known that I, BENJAMIN BRODIO, a citizen of the United States, and resident of the city of New York, State of New York, have invented certain new and useful Improvements in Superheat-Regulators, of which the following is a specification.

My invention relates to superheaters and has particular reference to devices whereby the degree of superheat may be automatically regulated and the superheater and engine protected against excessive temperatures. Its object is the provision of improved apparatus for this purpose.

The following description, to be read in connection with the accompanying drawings, which are hereby declared to form part hereof, will make clear the nature and operation of my device. In the drawings, Figure 1 is a longitudinal sectional view of a water tube boiler with my invention applied; Figs. 2^a and 2^b are enlarged views, partly in section and with portions broken away, of some details of Fig. 1; Fig. 3 is a detail like Figs. 2^a and 2^b of a modification; Fig. 4 is a view like that of Fig. 1, with parts omitted, of another modification; Fig. 5 is an enlarged detail of this modification; Figs. 6 and 7 are some details on a still larger scale; Fig. 8 is a sectional view of another type of boiler with my invention applied. Fig. 8^a is an enlarged detail of this form; Fig. 9 is a detail of a valve used in all of the forms so far referred to; and Fig. 10 is a view of a modification wherein electric means are employed for moving the damper.

The boiler 1 of Fig. 1 may be of any preferred construction. It is set in the housing 2, in the forward upper part of which there is the space 3, set off from the main boiler space by the wall 4, but communicating with it at the top through opening 5 and with the furnace 6 through the opening 7. The superheater 8 may be of any preferred construction. Steam pipe 9 conveys steam from the boiler 1 to the superheater 8; and pipe 10 carries the steam away from the superheater to the place of consumption. The superheater 8 is protected against direct radiant heat from the furnace 6 by means of fire-bricks 11, which are arranged

between it and the furnace in two rows, the bricks of each row being spaced from each other, and the bricks of the two rows being staggered relatively to each other. 12 is a connection to the stack.

The passage 5 is controlled by the two dampers 13 and 14, and gases can pass through it only when neither damper is entirely closed. The extent the passage is open is governed by the damper which is closed the farther. Each of the two dampers is connected to a counter-weight 15 by means of a flexible cable 16, passing over a fixed pulley 17. These counterweights are each of substantially the same weight as its damper.

Under the weights 15 are the two vertical cylinders 18 and 19 (see Figs. 2^a and 2^b), within which move the pistons 20 and 21, connected with the weights 15 by means of the piston rods 22 and 23.

The two ends of cylinder 18 are connected to valve 28 by the pipes 24 and 25; and the two ends of cylinder 19 are similarly connected to valve 29 by means of pipes 26 and 27.

To the valves 28 and 29 pressure fluid—which may be of any preferred kind, *e. g.*, water or air—is admitted by means of pipes 30 and 31 respectively. Pipes 32, 33, 34, and 35 are exhaust pipes and open to any desired points.

The valves 28 and 29 are identical in construction, and one of them is represented on an enlarged scale in Fig. 9. In the casing 40 the valve proper 41, of the balanced piston type, reciprocates. The port 42, to which the pressure fluid is carried by pipe 30 is always in communication with the annular space 43. With the valve in its central position, this annular space communicates with neither of the ports 44 or 45, which open into pipes 24 and 25 or 26 and 27. As the valve moves up it puts 42 into communication with 44, and 45 with the exhaust port 46; and as it moves downward it establishes communication between 42 and 45, and 44 and exhaust port 47.

The position of the valves in their casings is determined by the thermostatic elements 36 and 37. These two elements are located,

as will be seen from Fig. 1, in the upper portion of the superheater space 3 near the outlet 5, and in the superheated steam pipe 10 respectively. They are of an ordinary 5 commercial type, and act to move the valve stems 38 and 39 in one direction or the other with changes in the temperature at the points where the thermostatic elements are located. I have not shown the construction 10 of these elements in detail, as their specific structure forms no part of my invention. Any form of devices of this type that, directly or indirectly, is capable of giving the required motion to the valves in conformity 15 with the temperature changes over the temperature ranges involved will answer.

The action of the apparatus will now be readily understood. From Fig. 1 it will be clear that of the gases generated in the furnace a portion flows through the opening 7, between the fire-bricks 11, over the superheater 8 and out through opening 5 to rejoin the remaining portion which has passed over the first bank of tubes in the boiler, and 20 to pass together with them through the remaining passes of the boiler and out through 12 to the stack. It will be equally clear that the proportion of gases passing through the superheater space depends upon the position 25 of the two dampers 13 and 14. When either or both of them are closed, no gases will sweep over the superheater; and the proportion is always determined by the one which is lowered the farther.

30 Suppose that in the operation of the plant the temperature of the steam in 10 rises from some cause to a point above the predetermined desired maximum. The thermostatic element 37 will then give the valve 29 the 40 position indicated in Fig. 2^b, connecting the upper end of cylinder 19 to the exhaust and the lower end to the pressure supply. This will result in the piston 21 and its weight 15 moving upward and damper 14 moving 45 down. The flow of hot gases over the superheater will be somewhat checked and the superheat as a consequence somewhat cut down. The valves 28 and 29 are small relatively to the cylinders 18 and 19, and the motion of the pistons 20 and 21 and the connected dampers correspondingly slow. Before the damper 14 has sensibly passed the 50 position required the thermostatic element, sensitively following the change in temperature, gives the valve its neutral position in which it admits pressure to neither end of cylinder 19.

The opposite action, *i. e.* the action required when the steam temperature in 10 55 falls too low will be to admit pressure to the upper end of 19 and thus to raise the damper and allow a freer flow of gases over the superheater. During normal operation of the plant the regulation just described might be 60 sufficient. But when the steam consumption

is greatly reduced or entirely shut off, and during the firing up period, before there is any steam in the boiler, the thermostat 37 does not act, and the unchecked gas flow over the superheater would endanger it as 70 there would be no steam flow to carry off the heat. The action of the other thermostat and connected damper however prevent any damage. When no steam flows through the superheater, the gases passing along its elements have no heat abstracted from them and reach the exit 5 at a temperature substantially as high as when they enter the superheater chamber. With the steam flow reduced but not completely cut off, a proportionate rise over the normal temperature at 75 80 results. The effect on the thermostatic element 36 is such that it causes valve 28 to assume its lower position and to admit actuating pressure fluid to the lower side of piston 20, thus causing the piston to rise and the damper 13 to close partly or wholly. This 85 interrupts the gas flow through the chamber 3, and so prevents injury to the superheater.

With the temperature at the point 5 normal, no injury to the superheater by the hot gases can occur, and the device is set, so that at such times damper 13 is wide open. But even when this condition prevails, the temperature of the steam may be above the predetermined point; in which case damper 14 90 will assume the necessary partly closed position.

An arrangement similar to that described above, but having only one damper and one counterweight, is illustrated diagrammatically in Fig. 3. The two cylinders 18 and 19 with their valves 28 and 29 and thermostatic elements 36 and 37 are precisely as before in construction. The single counterweight 15^a 100 is acted on by the upper ends of the piston rods 22 and 23, which however are not connected with it. The counterweight 15^a is connected to the single damper by a flexible cord running over a fixed pulley, and is just 105 heavy enough to raise the damper as far as the positions of rods 22 and 23 permit.

When the temperature at thermostatic element 36 is above the desired point, valve 28 110 will admit actuating fluid to the under side of piston 20, and the damper will be lowered irrespective of the position of valve 29; and similarly if the steam temperature is too high, 37 will cause valve 29 to admit pressure to the cylinder 19 at its lower end and thus the damper to close. The damper will therefore always assume the position dictated by the thermostat tending to give it the more nearly closed position.

In the form shown in Fig. 4, and which 115 represents the form of this type at present preferred by me, there is also only one damper, designated 13^a, and one counterweight 15^a, and there is here in addition only one cylinder 18^a. There are however again 120 125 130

two valves 28^a and 29^a with their connected thermostatic elements 36 and 37 located respectively in the gas and steam spaces as before. In the enlarged diagrammatic view of Fig. 5 the two ends of cylinder 18^a will be seen to be connected with the two steam ports of each of the valves 28^a and 29^a by means of the pipes 24, 25, 26, and 27. Valves 28^a and 29^a are slightly modified from the form of Fig. 9 described above. Their form is illustrated on a larger scale in Fig. 6. The modification consists in the fact that a spring-controlled valve 48 is inserted into the lower exhaust pipe. This valve is seated by its spring, and remains seated at all times except when the valve 41 is down sufficiently to close port 45. The small pin 48^a then comes into contact with the valve 48 and unseats it, allowing the trapped fluid 20 to escape through pipe 48^b.

The lower part of the cylinder 18^a has leading from it the pipe 49, in which is inserted the valve 50, illustrated on an enlarged scale in Fig. 7. The casing 51 has fitted in its cylindrical interior the reciprocable valve 52, which the spring 53 tends to hold in position to interrupt flow through pipe 49, but which a sufficient amount of pressure from pipe 54 will move 30 along so flow through 49 is possible. Pipe 54 leads from some point in communication with the upper end of the cylinder 18^a.

To trace the operation of this device, suppose first that both the gas and steam 35 temperatures are excessive. Valve 28^a will assume the lower position and valve 29^a its position to the left, both admitting pressure to the bottom of cylinder 18^a. At the same time the fluid from the upper end of 40 the cylinder is free to escape through pipes 24 and 26 and the exhaust 47 of each of the valves 28^a and 29^a. Pipe 54 has no pressure in it and 50 remains closed.

If the gas temperature is too high and 45 the steam temperature normal, valve 29^a will have its mean position, and 28^a will act to close the damper the required amount just as if 29^a were absent. A corresponding state of affairs exists when the steam temperature is excessive and the gas temperature 50 normal.

If both temperatures are too low, valve 29^a will move to the right and valve 28^a up. Both will then admit pressure to the upper 55 end of the cylinder, pipe 54 will convey this pressure to valve 49 and open it, and the piston 20 is free to move down and open the damper.

Should the gas temperature be too high 60 and the steam temperature too low, valve 28^a will be in its lowest position and 29^a at the right. Pressure will then be admitted to the lower end of cylinder 18^a by valve 28^a. The pressure admitted by valve 65 29^a will be discharged through exhaust port

47 of valve 28^a, and valve 49 will have no pressure delivered to it by pipe 54. The piston 20 will consequently be urged upward and the damper be closed. The waste of pressure fluid involved in this case is not 70 serious, as the valves 28^a and 29^a are relatively very small; and moreover the condition of affairs stated will in practice occur only rarely if ever.

Another theoretically possible condition is 75 that the gas temperature is too low and the steam temperature too high. This condition is just opposite of the one just discussed and involves an inconsequential waste of pressure fluid through the exhaust port 47 of 80 valve 29^a. The damper will be closed just as in the preceding case.

In Fig. 8 is shown a boiler of a different type with my invention applied. The damper, 13^b, is here not of a reciprocating 85 kind but rotary, being keyed to and rotating with shaft 55. Also keyed to shaft 55 is the arm 56. Engaging slot 57 of arm 56 (see Fig. 8^a) is pin 58, which is carried by the piston rod 22^a. The cylinder 18^a, in 90 which the piston moves, and the valves and their connections to the cylinder are exactly as in the form of Figs. 4 and 5. The two thermostatic elements 36 and 37 are again respectively located in the path of the gases 95 after they have passed over the superheater and in the pipe 10 carrying the superheated steam.

The action is strictly analogous to that of Figs. 4 and 5, the upward motion of the 100 piston rotating the damper 13^b into its closed position, and the downward motion opening it.

In the form of my invention shown in Fig. 10 there are shown electrical means of 105 moving the damper 13^a. From the line 59 current is carried through the pole-changing switch 60 to the motor 61. The motion of the motor is geared down by any preferred means the proper amount to the drum 110 62, on which is wound, or from which is unwound, the flexible cord 16, which runs over fixed pulleys 17^a and 17^b, and whose farther end is attached to damper 13^a.

The pole changer 60 is held in open position by springs 63 as long as neither of coils 64 or 65 is energized by current from transformer 66. In circuit with coil 65 is the switch 67, which is opened by coil 68, in series with coil 64, whenever current flows 120 through the latter. Switch 69 closes the circuit through coil 65, switch 67, and transformer 66, whenever it is in its position toward the right; and opens this circuit and closes the one through coil 64, coil 68, and 125 transformer 66 whenever it is in its position toward the left. Similarly, switch 70 closes the first named circuit, i. e. through coil 65, switch 67 and transformer 66, in its upward position; and breaks this and closes the 130

other circuit, *i. e.* through coils 64 and 68 and transformer 66, in its downward position. It should be noted that if either of the switches 69 or 70 makes the circuit through 5 coil 68, the circuit through coil 65 is broken at switch 67.

The position of the switches 69 and 70 is controlled by the thermostatic elements 36^a and 37^a. With the temperatures too high 10 these thermostats close switches 69 and 70 toward the left and downwardly respectively; and with the temperatures below the desired points, these switches close toward the right and upward respectively.

15 With current flowing through coil 64, and pole changer 60 thrown to the left as a consequence, motor 61 moves to partly close damper 13^a. On the other hand, with pole changer 60 drawn to the right by coil 65, the 20 motor moves to raise the damper. The motion of the motor is geared down so far that before the damper has sensibly passed the correct position the thermostatic elements have adjusted themselves to the changed 25 condition and the motion of the motor is stopped. It will be evident that proper safety devices will be used in practice to prevent motion of the drum 62 and damper 13^a beyond a certain point in either direction, 30 so that no damage can result from this cause.

When the temperatures at the thermostats are as desired, the switches 69 and 70 are held in open position by springs 71.

35 It will be clear that the details of my invention may be varied in a great number of particulars without departing from its spirit. Thus the specific form of valves used in the form employing pressure fluid 40 may be different from that shown, as their structure does not enter into my invention. One variation I wish to point out regards the location of the thermostat reacting to the gas temperature. Under some circumstances it is desirable to locate it at some 45 other point than at the outlet from chamber 3, and by showing and describing it as located there I do not wish to be understood as limiting myself to that particular position. It will prove desirable in some cases 50 to locate it near the entrance or near the middle of the chamber.

These and similar variations will occur in practising my invention, and the appended 55 claims are meant to include them.

What I claim is:—

1. In apparatus of the class described the combination of a chamber, a superheater in 60 said chamber, said chamber having openings for the entrance and exit of heating gases, and means acting responsively to the temperature of the gases to control the passage of the gases through said chamber.

2. In apparatus of the class described the 65 combination of a chamber, a superheater in

said chamber, said chamber having an inlet and a damper-controlled outlet for heating gases, and automatic means to move said damper toward its open position when the gas temperature at the outlet falls below a 70 predetermined point and to move it toward its closed position when the gas temperature rises above a second predetermined point.

3. In apparatus of the class described the combination of a chamber, a superheater in 75 said chamber, said chamber having an inlet and an outlet for heating gases, a damper controlling said outlet, operating means for said damper, means tending to cause said operating means to act in response to the 80 temperature of the gases, and other means to make them act in response to the temperature of the steam.

4. In apparatus of the class described the combination of a chamber, a superheater in 85 said chamber, said chamber having an inlet and an outlet for heating gases, a damper controlling said outlet, operating means for said damper, means tending to cause said operating means to move the damper toward 90 its closed position when the temperature of the gases leaving the chamber is above a predetermined point and to move it toward its open position when it is below a second predetermined point, and other means tending 95 to cause said operating means to move the damper toward its closed position when the temperature of the steam leaving the superheater is above a predetermined point and to move it toward its open position 100 when it is below a second predetermined point.

5. In apparatus of the class described the combination of a chamber, a superheater in 105 said chamber, said chamber having an inlet and a damper-controlled outlet for heating gases, operating means for said damper, means tending to cause said operating means to move the damper toward its closed position when the temperature of the gases 110 leaving the chamber is above a predetermined point and to move it toward its open position when it is below a second predetermined point, and other means tending to cause said operating means to move the damper toward its closed position when the temperature of the steam leaving the superheater is above a predetermined point and to move it toward its open position when it is below a second predetermined point, those 115 of the two means, tending to make the damper-operating means act, prevailing which tend to cause them to move the damper toward its closed position.

6. In apparatus of the class described, the 120 combination of a boiler, a furnace, a superheater, means to pass a portion of the gases directly from the furnace over the superheater, means to control the relative amount 125 of gases so passed over the superheater, said

means acting in response to the temperature of the gases leaving the superheater.

7. In apparatus of the class described, the combination of a boiler, a furnace, a superheater, means to pass a portion of the gases directly from the furnace over the superheater, means to control the relative amount

of gases so passed over the superheater responsive to the temperature of either the gases or the steam leaving the superheater, and assuming the position dictated by whichever of the two tends to make the amount smaller.

BENJAMIN BROIDO.
